UNITED STATES PATENT OFFICE.

EDWARD P. BEACH, OF NEWARK, NEW JERSEY, ASSIGNOR TO UNGER BROTHIERS, OF SAME PLACE.

DESIGN FOR A SCARF-PIN.

SPECIFICATION forming part of Design No. 20,508, dated February 10, 1891.

Application filed December 26, 1890. Serial No. 375,862. Term of patent 3½ years.

To all whom it may concern:

Be it known that I, EDWARD P. BEACH, a citizen of the United States, residing at Newark, in the county of Essex and State of New Jersey, have invented and produced a new and original Design for Scarf-Pins; and I do hereby declare the following to be a full, clear, and exact description of the invention, such as will enable others skilled in the art to which it appertains to make and use the same, reference being had to the accompanying drawing, and to letters of reference marked thereon, which form a part of this specification.

Referring to said drawing, the same represents a front elevation of my newly-designed scarf-pin, and the one view is deemed sufficient to fully illustrate my design.

The leading feature of the design consists

in the peculiar conformation of the head and body of the pin, which is in the form of a scroll or spiral *a*, the thread of which is round in cross-section and tapers gently to and ends in the body of the pin *b*, which gradually tapers to the point, as indicated in the drawing.

What I claim, and desire to secure by Letters Patent of the United States, is—

The design for a scarf-pin herein shown and described.

In testimony that I claim the foregoing I have hereunto set my hand this 19th day of December, 1890.

EDWARD P. BEACH.
